UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR A DRESS

Application filed November 30, 1931. Serial No. 41,911. Term of patent 3½ years.

To all whom it may concern:

Be it known that I, DOROTHY LONG, a citizen of the United States, and a resident of New York, Borough of Manhattan, in the county of New York and State of New York, have invented the new, original, and ornamental Design for a Dress, of which the following is a specification.

Reference is had to the accompanying drawings forming part thereof wherein the essentials of the design consist of arranging the parts to present the formation of V-shaped motifs in the front, back and sides,

some of which are inverted and positioned so that the apices of some of the pairs of motifs will meet.

Figure 1 is a front view of a dress showing my new design.

Figure 2 is a side view of the dress shown in Figure 1.

Figure 3 is a rear view of the dress shown in Figure 1.

I claim:

The ornamental design for a dress substantially as shown.

DOROTHY LONG.
